UNITED STATES PATENT OFFICE.

HENRY A. WRIGHT, OF HALLS, TENNESSEE.

RAILWAY-MAIL-DELIVERY APPARATUS.

Application filed February 19, 1926. Serial No. 89,394.

This invention relates to apparatus for effecting delivery of mail and the like to and from moving railway cars.

The primary object of the invention is to provide a mail delivery apparatus of the above kind which is extremely simple and durable in construction as well as efficient in operation.

A further object of the present invention is to provide a mail delivery apparatus of the above kind by means of which the desired transfer of mail may be effected without danger of damaging the mail bags or losing the contents thereof during the transferring operation.

Still another object of the invention is to provide means for supporting the mail bags for delivery to or from a moving railway car, in such manner that accidental displacement of the mail bags from their proper position for delivery is rendered unlikely.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views:

Figure 1 is a fragmentary side elevational view illustrating a railway mail delivery apparatus constructed in accordance with the present invention, and showing the various parts related as they would be immediately after a mail bag has been delivered from a mail car and another mail bag delivered thereto.

Figure 2 is a horizontal section taken substantially upon line 2—2 of Figure 1.

Figure 3 is an enlarged top plan view of one of the swinging mail delivering and receiving arms mounted in the mail car.

Figure 4 is a sectional view taken substantially upon line 4—4 of Figure 3;

Figure 5 is a transverse section taken substantially upon line 5—5 of Figure 4;

Figure 6 is a transverse section taken substantially upon line 6—6 of Figure 5, and

Figure 7 is a horizontal fragmentary section taken on line 7—7 of Figure 1.

Referring more in detail to the drawings, 55 indicates a conventional form of railway mail car having a side doorway or opening 6, and in accordance with the present invention, an upright post 7 is rigidly mounted

within the car adjacent each side of the doorway or opening 6. The lower ends of the posts 7 are preferably fixed to brackets 8 which are bolted to the floor of the car, and the upper ends of the posts are preferably fixed in brackets 9 bolted to the ceiling of the car as shown.

Pivotedly mounted for horizontal swinging movement upon each of the uprights or posts 7 is a pair of angular mail delivering and receiving arms 10 which are arranged in spaced super-imposed relation and have forks 11 rigid with their free ends. Each arm may be provided at its inner end with

a hub 12 journaled upon the associated post 7 between a pair of collars 13 which are secured on the post in proper spaced relation by means of set screws 14 or the like. The arms 10 are thus mounted for horizontal swinging movement so as to be capable of

moving to a position within the car through the door opening as illustrated with respect to one of the arms in Figures 1 and 2, or positioned outside of the car as illustrated with respect to the remaining arms in said figures. For facilitating the swinging of the arms 10, the hubs 12 of the latter may be provided with rigid handles 15 which are in convenient reach of the mail-car attendant. By reason of the angular form of the arms 10 and the manner of mounting the same upon the posts or uprights 7, said arms will be disposed to project outwardly through the door opening and then longitudinally of the car outside of the latter when the arms are in their outwardly swinging position, the pair of arms at one side of the opening projecting away from the arms at the other side of the door opening, as shown.

The forks 11 are of similar form, and each embodies a plurality of laterally resilient prongs, the outer or end ones of which are longer and have their free ends outturned, and the inner or remaining ones of which

have enlarged free end portions 16 which are tapered at their sides in opposite directions, for purposes which will presently be made apparent.

The invention further contemplates a pair of forks 17 adapted to be suitably or rigidly supported beside the railway track so as to face away from each other in opposite directions and to lie in the same vertical longitudinal and horizontal planes. The forks 17 are also supported in a horizontal plane be-

arms 10 or each pair are supported so that the forks 11 of the arms 10 will respectively pass above and below the forks 17 when the arms are in their outwardly swung position 5 and the car passes the point at which the forks 17 are mounted. The forks 17 are preferably rigidly formed upon the ends of a horizontal bar 18 which has an outwardly and laterally offset intermediate portion rigidly secured to the upper ends of a pair of upright posts 19 suitably rigidly mounted beside the railway track. The posts 19 may be braced by a horizontal connecting bar 20 whose ends are rigidly secured to the posts 10 at a point below their upper ends. By offsetting the bar 18, the posts 19 may be positioned in sufficiently spaced relation to the car to permit the free passage of the arms 10 and their forks 11 without striking said post 19 as will be clearly apparent upon observing Figure 2.

A further pair of forks 17^a are supported beside the railway track below the forks 17 and so as to face away from each other. The forks 17^a are rigidly formed upon the ends of a bar 18^a which is jointed intermediate its ends as at 30, with the pivot of its joint attached to a horizontal brace bar 20^a connecting the posts 19 and arranged below the plane of the lower arms 10. Each fork 17^a is thus carried by a vertically swinging arm of the bar 18^a so as to be capable of occupying a raised or operative horizontal position as shown with respect to one fork 17^a in Figure 1, or a lowered inoperative position as shown with respect to the other fork 17^a in said figure. Means is provided to releasably maintain each fork 17^a in either raised or lowered position, and such means preferably embodies the provision of each post 19 with a pair of spaced superposed transverse openings 31 adapted for selective reception of a supporting pin 32, whereby the pin of each post will hold the associated arm of the bar 18^a raised when placed in the upper opening and prevent undue lowering of such arm when placed in the lower opening, the bar arm resting on the pin in each instance.

The present invention further contemplates a mail bag suspending bar 21 adapted to occupy a vertical position in use so as to pass between the prongs of the forks 11, 17 and 17^a. The bar 21 is provided at its upper end with a cross bar 22 adapted to rest upon the prongs of the fork supporting the same whereby a mail bag 23 attached to the bar 21 may be effectively supported by such fork. For facilitating detachable attachment of the mail bag to the bar 21, the lower end portion of the latter is provided with a longitudinal series of transversely elongated spaced slots 24 adapted for selective reception of the usual strap 25 upon the end of the mail bag.

65 As shown clearly in Figures 3, 5 and 6,

the bar 21 is tapered toward its opposite longitudinal edges to provide substantially feather or rounded edges which, in connection with the oppositely tapered free end portions of the inner prongs of the forks 11, 17 and 17^a, ensures ready passage of the bar 21 between said prongs when the mail bag supporting bar 21 is transferred from one fork to another during the operation of the apparatus. By reason of the enlarged form of the inner prongs of the forks, a restricted entrance is provided between the prongs which is narrower than the thickness of the bar 21 so that the bar 21 must be sprung past the enlarged free end portions of the prongs of the forks. The bar 21 is thus effectively held in place between the prongs of the forks so as to be capable of forcible removal although not capable of accidental displacement under ordinary conditions.

Assuming that the car is running to the right of Figure 1, the left hand mail bag supporting bar 21 is initially engaged between the prongs of both of the forks 11 of the arms 10 mounted at the left hand side of the doorway 6. By reason of the engagement of the bar 21 by the prongs of both of the forks 11 at this side of the doorway, the bar 21 and the attached mail bag 23 are effectively steadied and held against lateral swaying movement. In this operation the right hand supporting bar 21 is initially engaged between prongs of the right hand fork 17 mounted beside the railway track. Upon passage of the car the left hand supporting bar 21 will pass between prongs of the left hand forks 17 and 17^a so as to be removed by the latter from the left hand forks 11. The left hand mail bag 23 is thus delivered from the train and supported by the left hand forks 17 and 17^a as illustrated in Figure 1. While the above operation is taking place, the fork of the lower right hand arm 10 of the car will engage the mail bag supporting bar 21 and remove the same from the right hand fork 17, the right hand fork 17^a being lowered or inoperative, as shown. Upon continued movement of the car the right hand mail bag 23 will be carried along with the car supported by the fork 11 of the lower extended arm 10 at the right hand side of the door opening 6 so that the right hand mail bag 23 is delivered to the train. This right hand mail bag may be swung into the car upon swinging the lower right hand arm 10 horizontally from its extended position to a position within the car, as is apparent. It is to be understood that mail may be delivered or received by the forks at either side of the car door, depending upon which direction of travel is taken by the car. In any case, only the lower arm 10 at the receiving side of the door and the upper fork 17 at the delivering

- side of the device mounted beside the truck will be placed in operative position while both of the arms 10 at the delivering side of the door and both forks 17 and 17^a at 5 the receiving side of the device mounted beside the track will be extended or employed for respectively supporting the mail bag to be delivered from the car and receiving such bag when delivered. It is also to be understood 10 that the supporting bar 21 for the mail bag to be delivered from the car will be engaged with the forks of the active pair of arms 10 before the latter are swung outwardly of the car.
- 15 From the foregoing description it is believed that the construction and operation as well as the advantages of the present invention will be readily understood and appreciated by those skilled in the art.
- 20 Minor changes may be made without departing from the spirit and scope of the invention as claimed.
- What I claim as new is:
1. In a railway mail handling apparatus of the character set forth, a supporting frame structure designed to be placed adjacent a railway line and comprising a pair of spaced upright members and transversely extending vertically spaced cross members 25 connecting therebetween, a mail bag handling arm comprising a straight inner portion arranged parallel with and upon one side of one of said cross members, the inner end of said inner portion being pivotally secured to the adjacent cross member, an intermediate portion extending from the free end of said inner portion at an obtuse angle with respect to the same and an outer portion extending from the free end of said intermediate portion in offset parallel relation with the inner portion, a mail bag engaging element projecting from the free end of the outer portion of said arm, and removable means carried by an upright member 30 designed to engage beneath the inner portion of the arm to normally maintain the same in horizontal position, said retaining means being shiftable to allow the arm to be raised or lowered as desired.
  2. In a railway mail delivery apparatus, a mail bag suspending bar tapered toward its opposite longitudinal edges, and provided with means at one end for facilitating attachment of a mail bag thereto, and a rigid cross bar upon the other end of the mail bag suspending bar adapted to rest upon the upper edges of prongs of a mail bag suspending fork between the prongs of which said suspended bar is adapted to pass, the means for facilitating attachment of a mail bag to the mail bag suspending bar comprising a longitudinal series of transverse slots provided in an end portion of said mail bag suspending bar for selective reception of a mail bag strap.

In testimony whereof I affix my signature.

HENRY A. WRIGHT.
